Primary Examiner — Mehri F Bajoul**CLAIM**

The ornamental design for a basketball bean bag tossing game, as shown and described.

DESCRIPTION

FIG. 1: Top plan view of a basketball bean bag tossing game; FIG. 2: Bottom plan view of the basketball bean bag tossing game shown in FIG. 1;

FIG. 3: Left-side view of the basketball bean bag tossing game shown in FIG. 1;

FIG. 4: Right-side view of the basketball bean bag tossing game shown in FIG. 1;

FIG. 5: Front plan view of the basketball bean bag tossing game shown in FIG. 1;

FIG. 6: Rear plan view of the basketball bean bag tossing game shown in FIG. 1; and,

FIG. 7: Top perspective view of the basketball bean bag tossing game shown in FIG. 1.

The evenly dash-dash broken lines in the drawings depict environmental structure of the basketball bean bag tossing game that form no part of the claimed design.

The terms "Deep Shot", forming part of the claimed design, is a registered trademark of Mark Theodor Wolters.
